CHARLES WHITNEY MORDEN, OF PORTLAND, OREGON, ASSIGNOR TO CROWN-COLUMBIA PULP & PAPER COMPANY, OF PORTLAND, OREGON, A CORPORATION OF OREGON.

CHUCK FOR PAPER-ROLLS.

1,009,984.

Specification of Letters Patent. Patented Nov. 28, 1911.

Application filed April 22, 1911. Serial No. 622,825.

To all whom it may concern:

Be it known that I, CHARLES W. MORDEN, a citizen of the United States, and a resident of Portland, county of Multnomah, and 5 State of Oregon, have invented a new and useful Improvement in Chucks for Paper-Rolls, of which the following is a specification.

My invention relates to chuck-like devices provided for use on the paper-roll supporting spindle of printing presses of the newspaper type, and has for its purpose to clamp the paper-roll rigidly in place on the spindle during the printing process.

15 My invention has for its object to provide a clutch-like device which may be put in place and removed again with great rapidity; also to assure that when the chuck is applied it will rigidly hold the paper roll 20 against rotating relatively to the shaft, or moving longitudinally on the latter; also, in cases where the core is made of paper, to avoid undue wear of that end of the core of the paper roll in which my chuck is inserted.

25 My invention further has for its object to so arrange the parts that in case the paper roll should start to rotate on the spindle while the paper is being unwound, the chuck will automatically tighten and prevent further slipping; and that this feature shall be 30 accomplished whether such loose rotation of the paper roll is clockwise or counter clockwise.

My invention also has for its object to permit 35 nearly a complete utilization of the paper wound on the core of the spool.

These features, and others secondary thereto, I attain by the devices illustrated in the accompanying drawings and hereinafter 40 fully described.

In the drawings: Figure 1 is a half longitudinal section and half side elevation, illustrating in a general way the details of construction of, and the manner in which my 45 device locks the core to the spindle; it also illustrates the operation of what I term the "locking collar"; Fig. 2 is a section similar to that shown in the preceding figure, and illustrates a modification in construction, 50 having for its purpose a reduced length; Fig. 3 is a side view of the inner sleeve or expansion member of my device; Fig. 4 is a perspective view of one of the segmental

chuck jaws mounted on said sleeve and expanded thereby; Fig. 5 shows a method of 55 assembling the segmental chuck jaws in the ring which holds them together; it being noted that one of the segmental jaws is made with a bevel on its inner face to permit its insertion in place; Fig. 6 is an inner side perspective of the "locking collar"; Fig. 7 is a partial elevation of the "locking collar"; and Fig. 8 is a detail of a particular form of spanner convenient for operating the 60 chuck.

The expansion sleeve, *a*, is formed with a plurality of peripheral cones *b*, and is adapted to be readily slipped on the spindle *c*, on which the paper roll is to be mounted. At one end of the spindle, *c*, is rigidly secured, 70 as usual, a set-collar *e*, provided with a set-screw *f* and formed with an integral peripheral tapered sleeve-like portion *g*, facilitating its insertion in the related end of the core, represented by *d*. The expansion 75 sleeve, *a*, is formed at its outer end with a peripheral flange *h*, formed with a cam face *i*, said cam face having a peripheral rim bevel as at *j*. The flange *h* is formed with a hole at *k*, for receiving a spanner wrench. 80 On the expansion sleeve, *a*, are mounted the segmental chuck-jaws *l*, and the latter are formed on the interior with a plurality of stepped peripherally bevel faces *m*, the incline of which conforms to the conical faces 85 *b* of the member *a*. The segmental chuck-jaws are formed with parallel peripheral flanges *n*, *n'* at their outer ends, and an intermediate groove, in which is located a ring *o* for holding the outer ends of the 90 chuck-jaws together.

As shown in Fig. 5, the chuck-jaw member *l'* is made with a bevel at *p*, so as to permit it to be moved into place after the companion chuck-jaw members have been assembled within the ring *o*. The inner ends of the segmental chuck-jaws *l* are formed with a peripheral groove *q*, in which to receive a snap ring *r*, for holding such inner ends together.

100 The cam-face *i* of the expansion sleeve, *a*, is formed at its highest point with a stop lug *s*, the purpose of which will presently appear. On the spindle *c*, in front of the expansion member *a*, is placed a locking collar *t*, provided with an integral locking 105

finger t' ; a perspective detail of said collar being shown in Fig. 6. The collar t is convexed in cross-section at its eye or bore and it is formed at u with a serration. Compare 5 Figs. 1 to 6. In order to then more securely lock the collar t in place, also to prolong its life indefinitely, I prefer to make it with an insert as at v , convex in cross section and provided on its inner face with the serrations as u ; and it is to be noted that the ends v' of the insert v are made with a bevel so as to have a key-like seat in the collar t , preventing the insert being moved out of place in one direction, and I provide a 10 set-screw w , formed with a point w' , as shown in Fig. 7, for holding the insert v against being moved out of place in the other direction. As the serrations u become worn away in service, by filing down slightly 15 either of the ends v', v' the insert v may be set out by the set-screw w , so as to again form a substantially perfect circle in the eye of the collar t . The latter, when placed on the spindle c , will not stand perpendicular 20 thereto but at a slight angle, and any further tilting of the collar will cause its serrations u to grip the spindle and lock the collar against being moved longitudinally along the spindle. This action is aided 25 by the convexity of the serrated surface u . In placing my chuck on the spindle, the expansion sleeve, a , and collar t must be so relatively arranged as to cause the finger t' of the latter to bear against the lowest part 30 of the cam-face i of the former.

The operation of my chuck is as follows: The tapered collar e is, in the first instance, rigidly set on the spindle c at the desired point to properly locate the paper-roll on 40 the spindle. Next the spindle c , with the tapered collar in place as mentioned, is slipped into the core d of the paper-roll and brought to the position shown in Fig. 1. The expansion-sleeve a , with the segmental 45 clutch-jaws l mounted thereon, is then slipped on the opposite end of the spindle and into the corresponding end of the core d , as shown in Fig. 1, bringing the left end of the core in contact with the flanges n of 50 the segmental chuck jaws l . A wrench of the type shown in Fig. 8 is then placed between the flanges n' of the chuck-jaws l and the flange h of the expansion sleeve a , and by then pushing against the laterally projecting handle ends of the wrench the segmental 55 jaws may be forced into the core d and brought to a position substantially as shown in Fig. 1. A partial expansion of the segmental chuck-jaws is now brought about 60 by driving the expansion sleeve, a , still farther in by a few light blows with a lead hammer delivered against the end of the expansion sleeve, causing its conical faces b to work under the bevel faces m of the segmental 65 chuck-jaws l ; the latter being pre-

vented from moving along the spindle by reason of their flanges bearing against the end of the core d . The locking collar t is next slipped on the end of the spindle c , brought to the position shown in Fig. 1, and 70 fixed in place by setting up the screw w , and thereby the insert v . The round end of the wrench z' is now inserted in the hole h of the expansion sleeve a , and the latter is rotated in order to cause a still further and 75 powerful expansion of the segmental chuck jaws l within the core; for since during such rotation the cam face i of the expansion sleeve, a , will bear against the finger t' of the collar t , and since the latter is locked 80 in place on the spindle, such rotation of the expansion sleeve will cause it to move inward and thus wedge its conical faces b under the inclined faces m of the segmental 85 chuck jaws thereby expanding the latter; and any subsequent looseness of the paper roll causing a tendency of the paper roll to rotate on the spindle, while being unwound, is counteracted by a corresponding tightening action, brought about, as mentioned, by 90 the movement of said cam face of the expansion sleeve over the finger t' of the stationary collar t . To release the chuck from the core d , after the paper has been unwound from the latter, force the point of the locking collar on the side opposite its finger t' outward from the flange h of the expansion sleeve, a , by means of the flattened end z' of the wrench z . This releases the collar, 95 and the expansion sleeve may then be readily forced out by inserting said flat end z' of the wrench between the flanges n' of one of the segmental jaws l and the flange of the expansion sleeve a . This releases the 100 clamping action of my chuck. To remove 105 the chuck from the core, the wrench z is again used, by placing it between the flange n' of the chuck-jaw segment l and the flange h of the expansion sleeve a , and then pulling on the lateral handle ends of the wrench. 110 This will pull out the whole chuck, for the perpendicular faces of the inclined surfaces of the expansion member and the segmental chuck jaws will engage with each other, so that the pulling out of the expansion sleeve, a , will drag with it the segmental chuck-jaws l . The operations above outlined can be very rapidly performed and with but little exertion.

The stop lug s , provided on the cam-face 120 i of the collar t of the expansion member a , is an important part, for it prevents the finger t' of the locking collar passing the highest point of said cam face.

In the modification illustrated in Fig. 2, 125 representing a shorter chuck embodying the principles of my invention, the expansion sleeve a' is formed with only a few peripheral cone faces b' and the segmental chuck jaws l' are provided with correspondingly 130

formed bevel faces m' . The recess h' is so formed as to permit the wrench end to be inserted therein for prying the parts apart; the recess in other respects corresponds to h in Fig. 1.

Except as mentioned, the construction of the parts of the type of my chuck shown in Fig. 2 is substantially like that shown in the other views, and the parts common to both, and not changed in construction or operation, are designated by the same reference characters.

It will be noted that the convex cross section of the spindle-engaging faces of the locking collar aids the holding of the latter against being moved out of position, for any strain imposed on one edge of the collar would tilt it and in so doing bind it in place on the spindle.

20 I claim:

1. A chuck for paper roll comprising an expansion sleeve adapted to be mounted on a spindle and formed with peripheral conical steps and also with a cam head; segmental chuck jaws adapted to be mounted on said conical steps of the expansion sleeve and formed on their inner faces with bevel steps corresponding with the conical steps of the expansion sleeve; means for removably holding the segmental chuck jaws on the periphery of the expansion sleeve; a locking collar adapted to be mounted on the spindle, the eye of said collar being formed convex in cross-section; the bearing face of the eye of the collar being made with longitudinal serrations; means for positively clamping said locking collar to the spindle; and said locking collar formed with an integral locking finger the extremity of which is adapted to bear and slide on said cam head of the expansion sleeve.

2. A chuck for paper roll comprising an expansion sleeve adapted to be mounted on a spindle and formed with peripheral conical steps and also with a cam head; segmental chuck jaws adapted to be mounted on said conical steps of the expansion sleeve and formed on their inner faces with bevel steps corresponding with the conical steps of the expansion sleeve; a locking collar adapted to be mounted on the spindle, the eye of said collar being formed convex in cross-section; a set-screw for clamping said locking collar on the spindle; and said locking collar formed with an integral locking finger the extremity of which is adapted to bear and slide on said cam head of the expansion sleeve.

3. A chuck for paper roll comprising an expansion sleeve adapted to be mounted on a spindle and formed with peripheral conical steps and also with a cam head; segmental chuck jaws adapted to be mounted on said conical steps of the expansion sleeve and formed on their inner faces with bevel

steps corresponding with the conical steps of the expansion sleeve; a locking collar adapted to be mounted on the spindle, the eye of said collar being formed convex in cross-section, and having a movable spindle-gripping portion, also made convex in cross-section and formed with longitudinal serrations on its spindle-engaging face; a set-screw for setting up the movable spindle-gripping portion of the locking collar; and said locking collar formed with an integral locking finger the extremity of which is adapted to bear and slide on said cam head of the expansion sleeve.

4. A chuck for paper roll comprising an expansion sleeve adapted to be mounted on a spindle and formed with peripheral conical steps and also with a cam head; segmental chuck jaws adapted to be mounted on said conical steps of the expansion sleeve and formed on their inner faces with bevel steps corresponding with the conical steps of the expansion sleeve; peripheral grooves formed at the extremities of said segmental chuck jaws and ring-like holding members removably inserted in said grooves; a locking collar adapted to be mounted on the spindle, the eye of said collar being formed convex in cross-section; the bearing face of the eye of the collar being made with longitudinal serrations on its spindle-engaging face; a set-screw for clamping said locking collar to the spindle; and said locking collar formed with an integral locking finger the extremity of which is adapted to bear and slide on said cam head of the expansion sleeve.

5. A chuck for paper roll comprising an expansion sleeve adapted to be mounted on a spindle and formed with peripheral conical steps and also with a cam head; segmental chuck jaws adapted to be mounted on said conical steps of the expansion sleeve and formed on their inner faces with bevel steps corresponding with the conical steps of the expansion sleeve; peripheral grooves formed at the extremities of said segmental chuck jaws and ring-like holding members removably inserted in said grooves; a locking collar adapted to be mounted on the spindle, the eye of said collar being formed convex in cross-section, and having a movable spindle-gripping portion, also made convex in cross-section and formed with longitudinal serrations on its spindle-engaging face; a set-screw for setting up the movable spindle-gripping portion of the locking collar; and said locking collar formed with an integral locking finger the extremity of which is adapted to bear and slide on said cam head of the expansion sleeve.

6. A chuck for paper roll comprising an expansion sleeve adapted to be mounted on a spindle and formed with peripheral conical steps and also with a cam head having

- opposite inclines; a stop at the highest point of such inclines; segmental chuck jaws adapted to be mounted on said conical steps of the expansion sleeve and formed on their inner faces with bevel steps corresponding with the conical steps of the expansion sleeve; means for removably holding the segmental chuck jaws on the periphery of the expansion sleeve; a locking collar adapted to be mounted on the spindle, the eye of said collar being formed convex in cross section; the bearing face of the eye of the collar being made with longitudinal serrations; means for positively clamping said locking collar to the spindle; and said locking collar formed with an integral locking finger the extremity of which is adapted to bear and slide on said inclines of the cam head of the expansion sleeve.
7. A chuck for paper roll comprising an expansion sleeve adapted to be mounted on a spindle and formed with peripheral conical steps and also with a cam head having opposite inclines; a stop at the highest point of such inclines; segmental chuck jaws adapted to be mounted on said conical steps of the expansion sleeve and formed on their inner faces with bevel steps corresponding with the conical steps of the expansion sleeve; means for removably holding the segmental chuck jaws on the periphery of the expansion sleeve; a locking collar adapted to be mounted on the spindle, the eye of said collar being formed convex in cross section; the bearing face of the eye of the collar being made with longitudinal serrations; a set-screw for clamping said locking collar to the spindle; and said locking collar formed with an integral locking finger the extremity of which is adapted to bear and slide on said inclines of the cam head of the expansion sleeve.
8. A chuck for paper roll comprising an expansion sleeve adapted to be mounted on a spindle and formed with peripheral conical steps and also with a cam head having opposite inclines; a stop at the highest point of such inclines; segmental chuck jaws adapted to be mounted on said conical steps of the expansion sleeve and formed on their inner faces with bevel steps corresponding with the conical steps of the expansion sleeve; peripheral grooves formed at the extremities of said segmental chuck jaws and ring-like holding members removably inserted in said grooves; a locking collar adapted to be mounted on the spindle, the eye of said collar being formed convex in cross section and having a movable spindle-gripping portion, also made convex in cross-section and formed with longitudinal serrations on its spindle-engaging face; a set-screw for setting up the movable spindle-gripping portion of the locking collar; and said locking collar formed with an integral locking finger

the extremity of which is adapted to bear and slide on said inclines of the cam head of the expansion sleeve.

9. A chuck for paper roll comprising a shaft, a set collar adjustably mounted on one end thereof and provided with a tapered sleeve adapted to be inserted in one end of the core of the paper roll; an expansion sleeve mounted on the opposite end of the spindle and formed with peripheral conical surfaces arranged in steps, and also formed with a cam head having opposite inclines, and a stop at the highest point of such inclines; segmental chuck jaws mounted on the expansion sleeve and adapted to be inserted in the opposite end of the core of the paper roll; said segmental chuck jaws being formed on their inner faces with stepped bevel surfaces corresponding with said conical steps of the expansion sleeve; a locking collar mounted on the spindle in front of the cam face of the expansion sleeve, the eye of said collar convexed in cross section; the spindle-engaging surfaces of the collar being formed with longitudinal serrations; said collar formed with an integral locking finger the extremity of which is adapted to slide on said inclines of the cam head of the expansion sleeve; and a set-screw for clamping said collar to the spindle.

10. A chuck for paper roll comprising a shaft, a set collar adjustably mounted on one end thereof and provided with a tapered sleeve adapted to be inserted in one end of the core of the paper roll; an expansion sleeve mounted on the opposite end of the spindle and formed with peripheral conical surfaces arranged in steps, and also formed with a cam head having opposite inclines, and a stop at the highest point of such inclines; segmental chuck jaws mounted on the expansion sleeve and adapted to be inserted in the opposite end of the core of the paper roll; said segmental chuck jaws being formed on their inner faces with stepped bevel surfaces corresponding with said conical steps of the expansion sleeve; a locking collar mounted on the spindle in front of the cam face of the expansion sleeve, the eye of said collar convexed in cross section; and said collar formed with a movable spindle-gripping piece in its eye, also convexed in cross section; the spindle-engaging surfaces of said movable piece being formed with longitudinal serrations; said collar formed with an integral locking finger the finger the extremity of which is adapted to said inclines of the cam head of the expansion sleeve; and a set-screw for clamping said movable piece of the collar to the spindle.

11. In a chuck for paper roll, the combination with a spindle and a chuck thereon mounted comprising a sleeve formed with a wedge-like periphery, segmental chuck

jaws mounted on said sleeve and expanded thereby, and said sleeve also made with a cam head having opposite inclines; a locking collar adapted to be mounted on the 5 spindle, the eye of said collar being formed convex in cross section; the bearing face of the eye of the collar being made with longitudinal serrations; means for positively clamping said locking collar to the spindle; 10 and said locking collar formed with an integral locking finger the extremity of which is adapted to bear and slide on said inclines of the cam head of the expansion sleeve.

12. In a chuck for paper roll, the combination with a spindle and a chuck thereon mounted comprising a sleeve formed with a wedge-like periphery, segmental chuck jaws mounted on said sleeve and expanded thereby, and said sleeve also made with a cam 15 head having opposite inclines; a locking collar adapted to be mounted on the spindle, the eye of said collar being formed convex in cross section and having a movable spindle-gripping portion, also made convex in cross section and formed with longitudinal serrations on its spindle-engaging face; a set-screw for setting up the movable spindle-gripping portion of the locking collar; and 20 said locking collar formed with an integral locking finger the extremity of which is adapted to bear and slide on said inclines of the cam head of the expansion sleeve.

25

13. In a chuck for paper roll, the combination with a spindle and a chuck thereon mounted comprising a sleeve formed with a wedge-like periphery, segmental chuck jaws mounted on said sleeve and expanded thereby, and said sleeve also made with a cam head having opposite inclines; a locking collar adapted to be mounted on the spindle, the eye of said collar being formed convex 30 in cross section and having a movable spindle-gripping portion, also made convex in cross section and formed with longitudinal serrations on its spindle-engaging face; a set-screw for setting up the movable spindle-gripping portion of the locking collar; and 35 said locking collar formed with an integral locking finger the extremity of which is adapted to bear and slide on said inclines of the cam head of the expansion sleeve.
